UNITED STATES PATENT OFFICE.

JOHN WILLIAM EWART, OF MILL HILL, ENGLAND.

WATER-HEATER.

1,376,142.

Specification of Letters Patent. Patented Apr. 26, 1921.

Application filed November 26, 1919. Serial No. 340,829.

To all whom it may concern:

Be it known that I, JOHN WILLIAM EWART, a subject of the King of Great Britain, residing at "The Jeannettes," Mill Hill, Middlesex, England, have invented a new and useful Improvement in Water-Heaters, of which the following is a specification.

This invention relates to improvements 10 in water-heaters and to that class of apparatus which can be used to supply alternatively either a small quantity of boiling water in a short time or a larger quantity of hot water, suitable, say, for a bath, in a longer 15 time, say, twenty minutes or half an hour.

According to the invention my improved apparatus comprises a casing the upper part 20 of which is divided off as a water container by a partition which is of an inverted conical shape, that is to say, with the apex directed downward, and located beneath the said partitions, a correspondingly shaped boiler, that is to say, a boiler the shell of 25 which is of less diameter or width than the interior of the casing and which is of an inverted conical shape or V-shaped in vertical section, a space being provided between the partition and the upper surfaces of the boiler which communicates at its center with 30 a central vertical flue. The gases of combustion, therefore, from the gas burners below the boiler, impinge on the underside of the latter, pass up the inclined outer surface thereof and by reason of the inclination of 35 the said surface tend to cling thereto and so to give up a greater quantity of their heat, and then enter the downwardly directed passage between the partitions and boiler, the inclination of which passage again 40 causes the said gases to tend to cling to the heating surfaces, before finally escaping through the central flue. To increase the aforesaid clinging tendency of the gases to the surface of the boiler and partition I may 45 provide the said surfaces with protuberances, preferably in the form of studs, which check the flow.

The water container is formed with a downward annular extension below the partition and the cold supply water is fed into 50 this extension and thence supplied by a pipe to the bottom of the boiler.

The hot water from the boiler rises 55 through a pipe which extends partly up through the water in the container and terminates in a back-pressure valve. From the

bottom of the boiler a branch pipe extends to one passage of a two-way valve the other passage of which is in communication with a pipe within the container which extends 60 upward nearly to the water level. By this means by turning the plug of the valve either a small quantity of boiling water may be obtained quickly directly from the boiler or a larger quantity of hot water more 65 slowly from the container as may be required.

By reason of the inverted conical shape of the partition any water or condensation deposited upon the cold or cool surfaces will 70 collect at the lowest point or apex from which it will drip on to the upper surfaces of the boiler shell where it will be re-vaporized and so escape through the flue. A drain pipe for water of condensation is therefore 75 not required.

To enable the invention to be fully understood, I will describe it by reference to the accompanying drawing, in which:—

Figure 1 is a sectional elevation of a water 80 heater constructed according to the invention.

Fig. 2 is a sectional plan view thereof.

Fig. 3 is a sectional plan view of the delivery valve hereinafter described.

a indicates the casing and *b* the inverted conical partition which divides the said casing into an upper water chamber *c* and a lower or burner chamber *d*. The conical partition *b* is of a diameter somewhat less 90 than that of the casing *a*, and from its periphery there depends a jacket *e*, the lower edge of which is connected to the lower part of the casing *a* thus providing an annular extension of the water compartment *c* below 95 the level of the conical partition *b*. *f* is the water inlet pipe which extends down one side of the casing *b* to nearly the bottom of the water compartment *c* the upper end of the said pipe opening from the box *g* which 100 receives a supply of water from the pipe *h* controlled by the ball-cock *i*.

j is the chimney or flue which extends upward through the water compartment *c* from the center or apex of the conical partition *b* and thence at right angles so as to pass out at the side of the casing as clearly shown.

k indicates the boiler which, as above described, is of an inverted conical shape in 110 vertical section and is secured in the lower compartment *d* of the casing *a* in a position

such that a space l is left between the upper surface of the said boiler and the under surface of the conical partition b .

The boiler may be corrugated, as is shown 5 in Fig. 1, in the case of the undersurface, or provided with any other convenient form of protuberance or the like for the purpose of partially arresting the gases of combustion from the gas burner m located beneath 10 the said boiler, as above described.

n is the pipe by means of which water is fed from the bottom of the water container to the underside of the boiler k and o is the uptake pipe which extends upward from 15 the top of the boiler through the partition b and into the water compartment c where it terminates in the non-return valve p . q is the branch pipe from the bottom of the boiler and r is the two-way valve with one 20 passage of which the said branch q is in communication, s being the pipe in communication with the other valve passage and which pipe extends up through the water compartment c to nearly the water level.

25 The two-way delivery valve r may be of any suitable construction, and that which is shown in the drawing and in detail in Fig. 3 has been found a suitable construction which gives good results in practice. It 30 comprises the conical casing t having lateral openings t^1 into which open respectively the passages t^2 , t^3 in communication respectively with the pipes q and s . The conical casing t also receives the hollow plug u 35 which is provided with a port u^1 and with an external handle v by means of which it can be turned so as to bring the said port u^1 and thereby the interior of the plug in communication with either of the passages 40 t^2 and t^3 .

The apparatus operates as follows, that is to say, the water in the boiler is heated by means of the flames from the gas burner m in the usual way, the shape and arrangement of the boiler and adjacent part being such as to cause the gases of combustion to make good and efficient contact with the surfaces of the boiler. The said gases pass upward in contact with the conical bottom of 45 the boiler k and thence into the downwardly extending the passage or space l , whence they escape through the central flue j , the arrows in Fig. 1 indicating the direction of flow. The water in the boiler heated by the gases 50 then rises through the uptake pipe o and passes the valve p into the chamber c , this latter water being consequently gradually heated by conduction. As will be under-

stood, by turning the handle v of the delivery valve r so that the discharge outlet of 60 the said valve is in communication with the pipe s , then the heated water in the chamber c is delivered through the said pipe, whereas if the valve is turned so as to bring its discharge orifice in communication with 65 the pipe q , then heated water direct from the boiler is obtainable. In other words, either a large quantity of heated water suitable, say for a bath, or a smaller quantity of 70 boiling water can be obtained as may be required.

In practice a plate may be attached to the casing of the apparatus adjacent to the valve or to the body of the valve and marked to indicate the position to which the valve 75 should be turned to fulfil either of the requirements or to cut off the delivery.

To facilitate the ignition of the gas burners which may present some difficulty in view of the relatively large diameter of the 80 casing, I advantageously make use of a pilot-light which is swiveled to the casing so that it can be turned outward for ignition and then swung inward to serve for lighting the main burners. This pilot-light 85 may be left permanently burning if desired, to maintain the water warm.

Claims.

1. In a water heater of the kind herein referred to, a casing divided by an inverted 90 conical partition into an upper water container and a lower heating chamber, the water container being extended downward peripherally below the level of the partition, an inverted conical boiler provided with a 95 water inlet and with an up-take pipe extending into the water container and provided with a non-return valve and a two-way discharge or delivery valve in communication 100 respectively with the water in the water container and with that in the boiler, substantially as herein described.

2. In a water heater, a casing divided by a partition into an upper water chamber and a lower heating chamber, a boiler located in the heating chamber and provided with a water inlet which communicates with the water chamber, an up-take pipe provided on the boiler and extending into the water chamber, an automatically operating non-return check valve provided in the up-take pipe, a water outlet pipe for the boiler, a water outlet pipe for the water chamber, and a two-way discharge valve connected to said outlet pipes.

JOHN WILLIAM EWART.
